UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

SPINDLE AND BEARING.

SPECIFICATION forming part of Letters Patent No. 609,757, dated August 23, 1898.

[Application filed November 26, 1897. Serial No. 659,814. (No model.)

To all whom it may concern:

Be it known that I, GEORGE O. DRAPER, of Hopedale, county of Worcester, State of Massachusetts, have invented an Improvement in 5 Spindles and Bearings, of which the following description, in connection with the accompanying drawings, is a specification, like letters on the drawings representing like parts.

This invention has for its object the production of a novel bearing for spinning-spindles 10 of the type having a tapering pintle to fit a correspondingly-tapered bore in a bolster, the proper fit being effected by vertical movement of the bolster.

As will hereinafter more fully appear, the bolster is supported directly by the bolster-case and it is vertically adjustable thereon, said bolster being held in position by frictional engagement, whereby a very simple construction and ready adjustment are attained.

Figure 1 is a vertical sectional view of a spindle-bearing embodying one form of my invention. Fig. 2 is a similar view of another form thereof, and Fig. 3 is a partial sectional 25 detail of yet another form to be described.

The spindle S, having a tapering pintle to fit a correspondingly-tapered bore in the bolster, and the bolster-case A, having its lower end threaded to receive the usual nut B to 30 retain it on the rail C, and the sleeve-whirl W, attached to the spindle, may be and are of usual construction.

In my present invention the bolster is supported directly by and is vertically adjustable 35 in the bolster-case and is also held thereby from rotation.

Referring to Fig. 1, the lower end of the bolster B^x is counterbored at b and longitudinally slotted at b' and fits tightly into the 40 bolster-case, the expansibility of the slotted end of the bolster maintaining it in frictional engagement with the case, by which it is supported and maintained from rotation.

By moving the bolster up or down in the 45 case the proper fit of the pintle of the spindle is effected, and the bolster is held by friction in such vertically-adjusted position.

The slotted end is counterbored at b to prevent any compression upon the adjacent portion of the pintle.

In Fig. 2 the bolster is practically turned

end for end, the counterbored expansible portion then engaging the bolster-case at or near its upper end.

The spindle step or end bearing D in both 55 instances rests on the bottom of the bolster-case and is entirely independent of the bolster.

A reversal of the construction described is shown in Fig. 3, wherein the upper end of the 60 bolster-case B^x is longitudinally slotted at b^y to provide expansibility, and the upper enlarged end b^z of the bolster B^y is frictionally held thereby in vertical adjusted position and is held from rotation.

Except at the portion in frictional engagement with the case the bolster is loosely fitted to permit some slight freedom of movement, although both ends of the bolster could be frictionally held, if desired.

Having described my invention, what I claim, and desire to secure by Letters Patent, is—

1. The combination with a bolster-case, of a bolster having an integral expansible portion arranged to frictionally engage the case and be supported thereby.

2. The combination with a bolster-case, of a bolster having an integral annularly-enlarged expansible portion adapted to telescopically enter and be frictionally held in vertically-adjusted position in the case.

3. A bolster-case having a closed lower end, a removable spindle-step held sustained by the lower end of the case, and a bolster having an integral expansible supporting portion arranged to frictionally engage and be sustained by the case in vertical adjusted position.

4. A bolster-case, and a bolster having an annularly-enlarged, expansible portion, arranged to fit into and be frictionally held in position by the case.

5. A bolster-case, and a bolster having an annularly-enlarged, counterbored end longitudinally slotted, said end being adapted to enter and be frictionally held in position in the case.

6. The combination with a bolster-case, of a bolster having a tapered bore to fit the pintle of the spindle, and having a spring-acting portion, arranged to frictionally engage and

be held by the bolster-case, said spring portion being counterbored to prevent cramping of the pintle adjacent thereto.

7. The combination with a bolster-case, of a bolster having an expandible supporting portion to frictionally engage and be held in adjusted position by the case, the expandible portion being interiorly recessed to prevent engagement with the adjacent part of the spindle-pintle.

8. The combination with a bolster-case, of a bolster mounted therein, an integral expand-

sible portion of one being arranged to engage frictionally a laterally-unyielding portion of the other, to retain the two members in vertically-adjusted relative position. 15

In testimony whereof I have signed my name to this specification in the presence of two subscribing witnesses.

GEORGE O. DRAPER.
